(57) CLAIM

I claim the ornamental design for a food station, as shown and described.

DESCRIPTION

FIG. 1 is a perspective view of the food station.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1; and,

FIG. 8 is a cross sectional view of half of the food station taken in the direction of Section 8-8 of FIG. 6.

The broken line portion of the figure drawings is included to show portions of the article that form no part of the claimed design.
